UNITED STATES PATENT OFFICE.

GEORGE BUCHANAN, OF WASHINGTON, PENNSYLVANIA.

DESIGN FOR A GRATE-FENDER.

Specification forming part of Design No. 5,321, dated October 24, 1871.

To all whom it may concern:

Be it known that I, GEORGE BUCHANAN, of Washington, in the county of Washington and State of Pennsylvania, have invented or produced a new and original Design for Grate-Fenders; and I do hereby declare that the following is a full, clear, and exact description thereof, reference being had to the accompanying drawing and to the letters of reference marked thereon.

The nature of my design for fire-fender is fully represented in the accompanying drawing, to which reference is made.

Figure 1 is a front view of fire-front grate, and my design for fender when viewed in cross-section.

A represents the fire-front, and B its grate. C represents my design of fender, in which D D are handles for manipulating it, and e e f feet or lugs for holding it in position with relation to the

grate B. The two feet or lugs e e project down on the inside of the bars h i of the grate B, and the foot or lug f projects down on outside of the bars h i. The fender-bars 1 2 3 4 5 6 are secured in or cast to the vertical bars l l and m. It will be observed that the handles D D and feet or lugs form part of the bars l l, and the foot or lug f is a continuation downward of the bar m; and it will also be observed that there is a shoulder, n, at the lower end of each of the bars l l and m, and that the fender is supported on the top bar h of the grate by these shoulders n.

What I claim as of my invention is—

A design for a grate-fender, as described and shown in the accompanying drawing.

GEORGE BUCHANAN.
